UNITED STATES PATENT OFFICE.

EDOUARD COTTARD, OF NEZEL, FRANCE, ASSIGNOR TO SOCIÉTÉ E. COTTARD & CIE., OF NEZEL, FRANCE.

MACHINE FOR THE PRODUCTION OF IRON TURNINGS.

1,216,548.

Specification of Letters Patent.

Patented Feb. 20, 1917.

Application filed June 22, 1914. Serial No. 846,461.

To all whom it may concern:

Be it known that I, EDOUARD COTTARD, citizen of the Republic of France, residing at Nezel, Seine et Oise, in the Republic of France, have invented new and useful Improvements in Machines for the Production of Iron Turnings, of which the following is a specification.

This invention relates to machines for the production of long and thin iron turnings in which the bar or rod from which the same are produced is operated upon simultaneously throughout a great part of its length by a large number of tools mounted on the same tool carrier insuring a large production.

According to the present invention, the longitudinal displacement of the bar, which receives also a movement of rotation is effected by means of a feeding arrangement which forms a thread on the bar and acts upon the part of the bar which has already been acted upon by the tools producing the iron turnings.

A machine thus arranged insures regular working, it occupies the minimum space and has a very large output.

In the accompanying drawings which illustrate the invention:

Figure 1 is a view of the whole machine, Figs. 2 and 3 are details of the arrangement for effecting rotation of the bar;

Fig. 4 is a section of the tool holder slide;

Figs. 5, 6 and 7 are details of the arrangement for effecting longitudinal movement of the bar.

On the base 1 of the machine, at one of its ends, is fixed a headstock 2 which serves as a bearing for a hollow shaft 3, provided with a ball thrust bearing 4. On the shaft 3 is keyed a sprocket wheel 5 for imparting to it a rotary movement and driven by a chain 6 from a sprocket wheel 7, keyed on a transmission shaft 8. The shaft 3 is also provided with a locking mandrel intended to communicate a rotary movement to the bar 16 from which the chips of iron will be cut off. This mandrel is formed by a sleeve 9 (Figs. 1, 2 and 3) on which are threaded the members 10 and 11 having conical openings 10^a and 11^a respectively which act on the ends suitably shaped, of small cylinders or blocks 12, 13, which are disposed radially and are adapted to slide in the recesses in the sleeve 9. The small cylinders 12, 13

are provided with rollers 14, 15 having a cutting edge which permits them to bite into the bar 16 to be treated when the former is moved longitudinally.

The bar 16 is first shaped in such manner as to have a cylindrical part 16, a conical part 17 and another cylindrical part 18 of smaller diameter than the first.

The conical part 17 of the bar extends throughout the length of the tool holder 19, provided with a large number of small high speed tools 20 maintained in place, in the tool holder by means of screws 21 (Figs. 1 and 4). The position of the tool holder relatively to the bar may be regulated by means of a screw 22 carried by a base 23 fixed to the framework 1 and in which the tool holder is suitably guided.

The part 18 of the bar passes into a hollow shaft 24 supported by a headstock 25, fixed to the framework 1 of the machine. The shaft 24 is provided with a mandrel 26 similar to the mandrel 9, with this exception that the rollers of this mandrel have their axes parallel to the bar and have their edges rounded so as to be able to roll on the bar without preventing longitudinal displacement of said bar. The shaft 24 is also provided with a casing 27 on which is fixed a sprocket wheel 28 connected by a chain 29 with another sprocket wheel 30, keyed on the transmission shaft 8. A ball thrust bearing 31 is interposed between the casing 27 and the headstock 25. In the casing 27 are fixed a die or screwing chuck 32 and a nut in two parts 33 and 33^a (Figs. 1, 5, 6 and 7). The screwing chuck 32 is formed by a universal chuck of known type, the jaws of which have been replaced by cutting dies 32^a. The nut 33, 33^a, being in two pieces, may be separated when desired to disengage the bar operated on. It is maintained closed by the screws 34.

The operation of the machine is as follows:—the bar, 16, 17, 18 to be treated, being shaped as stated, the end of the part 18 is threaded to the pitch of the die 32, 32^a. The bar thus formed is introduced into the machine as shown in Fig. 1; the mandrels 9 and 26 are locked as also are the chasers 32^a of the die 32; the shaft 8 in rotating imparts rotary movement to the shaft 3 which transmits its movement to the bar through the medium of the rollers 14, 15 of the mandrel 9 which holds this bar firmly.

The shaft 8 imparts also a movement of rotation to the hollow shaft 24 but the various sprocket wheels are so arranged that the shaft 24 turns more slowly than the shaft 3 and consequently than the bar 16, 17, 18. The differential movement permits the die to rotate at first around the threaded part of the section 18 of the bar and then to produce a thread on the part of said section which has not been previously threaded, whereby a longitudinal movement is imparted to the bar. When a thread of sufficient length has been formed, the end of the part 18 engages the nut 33, 33^a, which then alone 10 produces movement of the bar, the die having no other function than producing the thread. From the manner of mounting it will be seen that all reactions of the parts are sustained by the ball thrust bearings 4 and 31 and by the nut 33, 33^a which insures 15 efficient operation of the machine.

It will be seen that it is very easy to regulate the longitudinal movement of the bar; to do this, it is sufficient to change the 25 amount of the differential movement which may be effected by changing the diameter of the wheel 28 for example.

The ends of the tools 20 being located on 30 a parallel to the generatrix of the cone 17, it will be seen that it is sufficient to operate the screw 22 to regulate the thickness of the cut and consequently the degree of fineness of the iron turnings obtained on the machine.

Having now described my invention, what 35 I claim as new and desire to secure by Letters Patent is:

1. A machine for making iron turnings from a bar, comprising a number of cutting 40 tools arranged along the bar and movable toward and away from the bar, means for rotating said bar and means for feeding the bar longitudinally by forming a thread along the bar in the part which has been 45 acted upon by the tools, substantially as described and for the purpose set forth.

2. A machine for making iron turnings from a bar, comprising a number of cutting 50 tools arranged along the bar and movable toward and away from the bar, means for

rotating said bar, a die adapted to form a thread along the bar in the part which has been acted upon by the tools and a nut engaging the threads formed to feed the bar forward, substantially as described and for 55 the purpose set forth.

3. In a machine for making iron turnings, tools for cutting iron turnings from a bar, means for rotating said bar, a die adapted to form a thread along the bar in 60 the part which has been acted upon by the tools, a nut engaging the threads thus formed to feed the bar, a casing carrying the die and the nut, and means for rotating said casing in the same direction as the bar at a 65 lower speed, substantially as described and for the purpose set forth.

4. In a machine for making iron turnings, tools for cutting iron turnings from a bar, means for rotating said bar, a die adapted 70 to form a thread along the bar in the part which has been acted upon by the tools, a nut engaging the threads thus formed to feed the bar, a casing carrying the die and the nut, means for rotating said casing in 75 the same direction as the bar at a lower speed, a hollow shaft secured to the casing, a headstock for supporting said shaft and rollers mounted on the hollow shaft for supporting the bar, substantially as described 80 and for the purpose set forth.

5. In a machine for making iron turnings, tools for cutting iron turnings from a bar, a hollow shaft through which the bar extends, means for rotating said shaft, 85 blocks sliding radially in said shaft, rollers mounted on said blocks and adapted to impart to the bar a rotary movement, a nut screwed upon the shaft and engaging with said radial blocks, and means for feeding 90 the bar longitudinally by forming a thread thereon, substantially as described and for the purpose set forth.

In testimony whereof I have signed my name to this specification in the presence of 95 two subscribing witnesses.

EDOUARD COTTARD.
